Inventor:
Albert W. Morrell

United States Patent Office.

ALBERT W. MORRELL, OF NILES, MICHIGAN.

Letters Patent No. 101,756, dated April 12, 1870.

FEED-WATER REGULATOR AND LOW-WATER ALARM

The Schedule referred to in these Letters Patent and making part of the same.

I, ALBERT W. MORRELL, of Niles, in the county of Berrien and State of Michigan, have invented an "Automatic Feed-water Regulator and Low-water or Accident Alarm," of which the following is a specification.

Nature and Objects of the Invention.

The first part of my invention relates to the combination of a large cylinder (to be attached to a steam-boiler) float, small cylinder, piston, spring, and rod, with a globe or other valve located in the supply-pipe to the engine's pump. The object of this part of my invention is to regulate the supply of water to the pump with which the boiler is supplied by the quantity of water in the boiler.

The second part of my invention relates to the combination of an alarm with the large cylinder and float. The object of this part of my invention is to give warning of accident in the pump or failure of supply-water.

Description of the Accompanying Drawings.

Figure 1 is a sectional view of an apparatus embodying my invention.

Figure 2 is an enlarged longitudinal and transverse section of the alarm-valve.

Figure 3 is a view of the small cylinder and head of large cylinder detached, to be connected by any desired length of steam-pipe.

General Description.

A is the large cylinder, made strong enough to resist the pressure of steam, and connected with the boiler or steam-generator by the steam-pipe Q above the "true water-line," and below the "alarm water-line" by the water-pipe K, thus permitting the water in the cylinder to assume the same level with that in the boiler.

F is the float, which rises and falls with the water in the cylinder.

G is a stem, secured to the top of the float, working freely in the guide-pipe C, and connected with a valve at its upper extremity.

O is a valve in the head V of the large cylinder.

B is a small cylinder that is attached to the head of the large cylinder, and contains a piston, P, which is connected by the rod H with the valve D, which is located in the supply-pipe M N, between the tank and pump.

S is a spiral spring, which acts upon the upper side of the piston P.

Z is a hinged valve that makes the connection between the alarm W and the large cylinder A.

Fig. 2 is an enlarged view of the valve Z. The right-hand section shows the shape of the valve and

the valve-seat. Said valve is straight across the lower edge, where it forms a hinged connection with its support, and is scalloped to facilitate its working. In the left-hand section the valve is shown slightly tipped.

Y is a spiral spring attached to the side of the cylinder at its upper extremity and to the lever of the valve Z.

T is a test-pin.

Operation.

When the water in the boiler and cylinder evaporates to below the "true water-line," the float F sinks therewith and opens the valve O, permitting steam to pass from the large cylinder A into the small cylinder B, where it acts against the underside of the piston P, forcing it upward and opening the valve D, which permits the free passage of water from the tank to the pump, by which the boiler is supplied.

When sufficient water has been forced into the boiler to fill it to the "true water-line" the float, rising therewith, closes the valve O, shutting off the steam from the piston P, when, by the reaction of the spring S, the piston is forced downward, closing the valve D, thus preventing high water in the boiler.

When, through accident to the pump or failure of supply-water, the water in the boiler is evaporated to the "alarm water-line," the float F sinks therewith, and the pin X, in the stem G, strikes the lever of the alarm valve Z, opening the valve and permitting the steam to sound the alarm W, thus calling the attention of the attendant.

When the boiler is again filled to the "true water-line," the float rises and removes the pressure from the valve-lever at X, the spring Y recoils and closes the alarm-valve Z.

If, at any time, the attendant wishes to know whether the alarm be in working order or not, he can try it by pressing upon the test-pin T, which is connected with said valve, wherewith he can open the valve and try the alarm.

Claims.

The combination of the small cylinder B, piston P, spring S, and rod H, with a globe or other valve located in the feed-water pipe of a boiler, between the pump and tank, substantially in the manner and for the purpose above set forth.

2. The combination of the accident or low water alarm W with the feed-water regulator, substantially in the manner and for the purpose above described.

ALBERT W. MORRELL.
